CHARLES C. ABBOTT, OF PITTSFIELD, MASSACHUSETTS, ASSIGNOR TO ROBBINS, GAMWELL AND COMPANY, OF PITTSFIELD, MASSACHUSETTS, A COPARTNERSHIP.

AUTOMATIC SPRINKLER.

1,208,072.

Specification of Letters Patent. Patented Dec. 12, 1916.

Application filed June 22, 1916. Serial No. 105,281.

To all whom it may concern:

Be it known that I, CHARLES C. ABBOTT, a citizen of the United States, residing at Pittsfield, county of Berkshire, State of Massachusetts, have invented an Improvement in Automatic Sprinklers, of which the following is a specification.

This invention relates to the construction of automatic sprinklers and has for its object to provide a structure of this character which shall be compact, safe and durable, and quick and efficient when the temperature rises above the predetermined maximum. This I effect by compounding the leverage in such a manner that very slight strain is placed upon the solder which retains the parts of the locking and releasing member together, but great pressure is exercised the instant the solder is melted to disrupt the cap-retaining means with almost explosive effect, so that quick operation is insured wholly independently of the water pressure.

With these and other objects in view, I have devised the novel automatic sprinkler which I will now describe, referring to the accompanying drawing forming a part of this specification and using reference characters to indicate the several parts:—

Figure 1 is an elevation of my novel sprinkler, as in use; Fig. 2 a section on the line 2—2 in Fig. 1, looking in the direction of the arrows; Figs. 3 and 4 detail views of the brace detached; Figs. 5 and 6 detail views of the compression member detached; Figs. 7 and 8 views of the parts of the locking and releasing member detached; Fig. 9 a view of the compression plate detached; Fig. 10 a view of the cap detached, and Fig. 11 is a partial elevation, the position of the parts corresponding with Fig. 2.

The frame comprises a hollow hub 20 threaded to engage a socket in a water supply system, a yoke 21 and a block 22 which is tapped to receive a set screw 23 and carries a deflector 24. These parts may be of ordinary construction and design. The opening in the hub is closed by a cap 25 having a concave depression 26 in its outer face in which a convex faced compression plate 27 is seated. A ribbed gasket 38 is interposed between the cap and the end of the hub and the cap is provided on its underside with a corresponding rib 39, which pre-

vents displacement of the parts. The ball 55 and socket engagement of the compression plate with the cap distributes the pressure, when assembled, and insures uniform bearing of the cap on the hub. The cap-retaining means comprises a compression member 60 28, a brace 29 and a two-part locking and releasing member indicated as a whole by 30.

The compression member is provided with side flanges 31 each having an upper notch 32 and a lower notch 33. At the upper end 65 of the compression member is a resilient lip 34 which before assembling lies at an acute angle to the plane of the upper ends of the flanges. This lip is provided with a seat 35 adapted to receive the tip of the set screw, 70 as will be more fully described.

Brace 29 is a plate which is received freely between the flanges of the compression member and is shown as provided with a longitudinal rib to impart additional rigidity. 75 The ends of the brace are rounded, the upper end having its bearing at the intersection of the resilient lip with the back of the compression member, as at 36 (see Fig. 2), and the lower end having its bearing in a slot 80 37 in the top of the compression plate. In the assembled position, the brace lies obliquely to the axis of the hub, the position of the lower end being central. This enables me to make the structure as a whole 85 very compact with no parts projecting beyond the spreader and also insures that the brace will drop out of the way when the cap-retaining means is disrupted, as will be more fully explained. 90

Locking and releasing member 30 comprises an upper part indicated specifically by 40 and a lower part indicated specifically by 41. It should be understood that the terms "upper" and "lower" as applied to 95 said parts and to the notches in the flanges of the compression member which are engaged by said parts respectively, are used merely for convenience in description, as it is wholly immaterial in what position the 100 sprinklers are placed. They may in use be inverted, or placed horizontally, or in any intermediate position. Part 40, which I term the upper part, is provided with lugs 42 which in the assembled position engage 105 upper notches 32 in the flanges of the compression member, and with a central off-set 43 which lies between the flanges of the com-

pression member and acts to prevent lateral displacement. At the lower end of part 40 is an angle plate 44 having an opening 45. Part 41, termed the lower part, is provided at its lower end with lugs 46 which in the assembled position straddle the brace, on which the member bears, and engage lower notches 33 in the flanges of the compression member. Above the lugs is an angle plate 47 which is adapted to lie under and in contact with angle plate 44 on part 40 and is provided with an opening 48 registering with opening 45 but smaller than said opening. The parts of the locking and releasing member are secured together by means of a solder which will melt at a predetermined relatively low temperature, solder being placed between the parts above the angle plates, as clearly shown in Figs. 2 and 11, and also in the openings in the angle plates. As the opening in the lower angle plate is smaller than the opening in the upper angle plate, a pocket is formed from the solder which also passes through the opening in the lower angle plate. In assembling, the gasket, cap and compression plate are placed in position, as in Fig. 2. The resilient lip of the compression member is placed in engagement with the set screw, the ends of the brace are placed in engagement with the slot in the compression plate, and with the compression member back of the lip, and the locking and releasing member (the parts having of course been secured together by solder as described) is placed in position with the upper lugs in engagement with the upper notches and the lower lugs in engagement with the lower notches. The assembling operation is completed by turning the set screw down upon the resilient lip and locking it, whereby strain is placed upon the cap-retaining means as a whole. The tendency is to swing the lower end of the compression member toward the left, from the position shown in Figs. 2 and 11. This causes the locking and releasing member to bear on the brace and causes the respective ends of said member to bear against the walls of the upper and lower notches in the compression member. The pressure, however, is distributed between the component parts of the cap-retaining means in such a manner that relatively little strain is placed upon the solder. As soon as the temperature rises sufficiently to melt the solder, the tension of the set screw upon the resilient lip will cause a general tendency of the several parts of the cap-retaining means to fly apart. The parts of the locking and releasing member will separate, the lower end of the upper part swinging toward the right and the lower end of the lower part toward the left, the solder in the openings in the angle plates being sheared off by the sliding movement of said plates.

In practice, the parts of the cap-retaining means separate with a force and quickness that is practically explosive. The separation of the parts of the locking and releasing member releases the compression member, which swings outward toward the left from its position in Fig. 2, and releases the brace. The movement of the lower end of the compression member and of the lower end of the lower part of the locking and releasing member toward the left causes the upper end of the lower part of the locking and releasing member to act as a lever on the upper part of said member and swing it outward toward the right, the brace serving as a fulcrum for the lever. In practice the action is so quick that the instant the solder melts, all of the parts of the cap-retaining means are violently expelled from the yoke, leaving the cap free to be simultaneously lifted by the water pressure.

Having thus described my invention, I claim:

1. In an automatic sprinkler, the combination with a yoke having a set screw, a hub, a cap for closing the opening in the hub having a concave depression in its outer face and a compression plate having a corresponding convex face, of a compression member having a resilient lip engaged by the set screw, and flanges having upper and lower notches, a brace engaging said member and the compression plate, and a two-part locking and releasing member, one of said parts having lugs engaging the upper notches and an angle plate, and the other part having lugs engaging the lower notches and an angle plate registering with the other angle plate, said parts being secured together by low-melting solder.

2. In an automatic sprinkler, the combination with a yoke having a set screw, a hub, a cap for closing the opening in the hub having a concave depression in its outer face and a compression plate having a corresponding convex face, of a compression member having a resilient lip engaged by the set screw, and flanges having upper and lower notches, a brace engaging said member and the compression plate, and a locking and releasing member comprising upper and lower parts, said upper part having lugs engaging the upper notches and an angle plate with an opening, and the lower part straddling the brace and having lugs engaging the lower notches and an angle plate with an opening smaller than the first mentioned opening, said parts being secured together by low-melting solder which also fills the openings.

3. In an automatic sprinkler of the character described, cap-retaining means comprising a compression member having a resilient lip and flanges with upper and lower notches, a brace engaging said member back

of the lip, and a two-part locking and releasing member, the upper part having lugs engaging the upper notches and an angle plate, and the lower part straddling the brace and having lugs engaging the lower notches and an angle plate lying under the first mentioned angle plate, said angle plates being provided with openings to receive low-melting solder and the portions of said parts 10 above the angle plates being secured together by low-melting solder.

4. A locking and releasing member for automatic sprinklers comprising an upper part having at its lower end an angle plate 15 with an opening, and a lower part having at its lower end an angle plate lying below the first mentioned angle plate and having a smaller opening, said parts being secured together by low-melting solder which also fills 20 the openings in the angle plates.

5. A locking and releasing member for automatic sprinklers comprising an upper part having at its upper end lugs and at its lower end an angle plate with an opening, 25 and a lower part having at its lower end an angle plate with an opening and lugs, said parts being secured together by low-melt-

ing solder which also fills the openings in the angle plates.

6. Cap-retaining means for automatic 30 sprinklers comprising a compression member having a resilient lip, a brace engaging said member back of the lip, and a two-part locking and releasing member, said parts 35 engaging the upper and lower ends of the compression member and the lower part bearing on the brace.

7. Cap-retaining means for automatic 40 sprinklers comprising a compression member having a resilient lip and flanges with 45 upper and lower notches, a brace engaging said member back of the lip, and a locking and releasing member consisting of an upper part having lugs engaging the upper notches and an angle plate, and a lower part 50 having a bearing on the brace, lugs engaging the lower notches and an angle plate, said angle plates having registering openings and said parts being secured together by low-melting solder which also fills the 55 openings in the angle plates.

In testimony whereof I affix my signature.

CHARLES C. ABBOTT.
